UNITED STATES PATENT OFFICE

FRANCIS L. CHADWICK, OF DETROIT, MICHIGAN, ASSIGNOR TO WOODALL INDUSTRIES INCORPORATED, OF DETROIT, MICHIGAN, A CORPORATION OF MICHIGAN

VEHICLE BODY PANEL STRUCTURE

Application filed June 15, 1931. Serial No. 544,326.

My invention relates to body panels for automotive vehicles and has particular reference to such a panel constructed of composition fiber board provided with an upholstery covering and having an improved pocket structure on its finished side.

It has become customary to utilize fiber board panels for the interiors of automobile bodies, which board may be of various compositions, but which invariably possesses an inherent flexibility which is useful in making the panel conform to various curvatures in the body lines. Certain of these panels are provided with pockets the closure of which is normally maintained by a permanent tension imposed thereon, which tension sets up a stress in the panel that tends to distort it.

An object of my invention is to eliminate this tendency toward unsightly warping and to provide a simplified pocket structure secured to the face of a panel without any tendency toward distortion of the panel. In carrying out the object of this invention I contemplate the provision of a somewhat flexible frame member delineating the outer contour, except for the mouth, of the desired pocket. This frame is positioned upon the face of the panel and the corresponding edges of the fabric, of which the pocket is to be formed, is looped thereover and the double thickness of fabric stitched to the panel. A yieldable mouth to the said pocket is provided by positioning a coil spring under slight tension along the open side of the frame and encasing it within the corresponding side of the pocket fabric.

Another object of my invention is to offset the stress set up within the panel by reason of the aforesaid coil spring and thus eliminate the tendency created thereby to flex the panel out of its normal plane.

An important feature of the invention resides in the particular arrangement whereby the above mentioned rigidifying effect is secured by means positioned upon the unexposed side of the panel without increasing the maximum depth of the panel or, in other words, without utilizing rigidifying means which will project beyond the rear face of

the main body portion of the panel. This is important because it is desirable that the major portion of the rear face of the panel lie substantially within a given plane in order to eliminate any bulges or distortions which might otherwise appear upon the visible surface of the panel when the said panel is positioned against the backing which it is designed to cover.

Various other objects and meritorious features of the invention will become apparent from the following description taken in conjunction with the drawing, wherein like numerals refer to like parts throughout the several figures and wherein:

Fig. 1 is a front elevation of a panel embodying my improved pocket assembly,

Fig. 2 is a rear elevation thereof, partly broken away,

Fig. 3 is an enlarged elevation of the pocket construction per se,

Fig. 4 is a section through the panel structure perpendicular to the open mouth of the pocket,

Fig. 5 is a section through the panel at right angles to Fig. 5,

Fig. 6 illustrates a somewhat modified assembly, and

Fig. 7 is a section through 7-7 of Fig. 6.

The panel per se is illustrated by the numeral 10 and is cut to shape as depicted, the particular panel shown being adapted to fit the rear door of an automobile. These panels, as hitherto stated, are usually cut from sheets of fiber board which are inherently flexible. In conjunction with the improved pocket structure hereafter to be defined it is preferable that a fiber board of a thermoplastic nature be utilized. Such sheets may be embossed by the ordinary die stamping process and will retain their shape thereafter.

The edges of the panel are provided with elongated apertures 12 adapted to receive fastener elements which in turn function to secure the said panel to a supporting frame arranged on the interior of the door. The panel illustrated has been subjected to the embossing process heretofore mentioned and a portion of the interior expanse of the panel

is offset from the marginal portion 14 of the panel, the offset portion being delineated by the compacted line of deformation 16. The die stamping procedure compacts the panel material along this line of deformation 16, thereby increasing the rigidity of the panel as a whole.

Trim material 18, covering the interior of the panel, is folded over the edges thereof as at 20 and, after being stretched taut, preferably glued thereto. The said material is stitched to the panel as at 22 along the compacted line of deformation 16 produced by the embossing of the panel, and the pocket structure is assembled as hereafter described.

A frame 24, which may be of wire as illustrated, to which the outer edges of the pocket fabric are secured is positioned upon the inner face of the panel. This frame may be of any desired contour but for purposes of illustration we have disclosed it as conforming substantially in shape to the offset interior expanse of the panel. The extremities of the frame 24 are bent into eyelets 26 to which the opposite ends of a coil spring 28 are secured.

Coil spring 28, which is to maintain a normal closure of the mouth of the pocket, is preferably under slight tension and this would normally create a tendency to buckle the flexible panel material. This panel material is composition fiber board held together by a suitable binder. It is common practice to employ a moisture resistant binder, such as an asphaltum compound, which is responsive to heat and pressure to permanently assume a shape to which it has been deformed. To eliminate this tendency I provide, in conjunction with the spring, a substantially inflexible support for the spring, which is arranged on the opposite side of the panel and takes the tension of the spring, relieving the panel of such stress. Otherwise the panel would frequently deform under the tension of the spring and retain such deformed shape, spoiling the appearance of the panel and causing the pocket to remain open because of the panel bending.

For purposes of illustration I have shown a strip 30 of relatively rigid material arranged on the opposite face of the panel and held in place by brads 32. The ends of the pocket frame 24 are positioned by means of any suitable type of fastener element such as the looped metal strip 34, the extremities of which, after being drawn through the panel and strip 30, are flattened out as illustrated. It is to be noted that the thickness of the strip 30 is substantially equal to the depth of the embossment on the interior expanse of the panel. In other words, the rigidifying strip 30 is positioned on the rear face of the embossed portion of the panel and its thickness is such that it does not project rearwardly beyond the rear face of the main body por-

tion of the panel. While the portion 14 of the panel has been referred to heretofore as the marginal portion, it will be understood that it constitutes the main body portion, particularly because of the fact that it is this portion which is positioned against a back which is designed to function as a support for the panel. If the said supporting surface lies in a plane or constitutes a smooth curved surface, any projection of the reinforcing strip 75 rearwardly beyond the rear face of said portion would create a bulge in the interior expanse of the panel.

From the foregoing it will be apparent that frame 24 is first positioned by means of the element 34 and the pocket fabric 36 subsequently secured in the manner illustrated. The side edges of the pocket fabric are rolled over the frame 24 and folded back to form a double thickness of cloth, which double thickness is secured by stitching, as indicated at 38, to the panel 10. The edge which is to constitute the mouth of the pocket is looped over the coil spring 28 and stitched, as at 40. In this way the edges of the pocket are fixedly positioned upon the panel and rigidly held in place, while the mouth of the said pocket is normally held against the face of the panel to close the opening of the pocket by means of the yieldable spring 28. The tension in the spring 28 is taken by the relatively rigid strip 30 extending in superposed relation to the said spring on the opposite face of the panel and lying substantially within the plane of the main body portion thereof.

As a modified structure, I have illustrated a panel 42 which includes an embossed corrugation 44 extending across the panel along the line extending between the eyelets 26 of the frame member 24. This embossment substantially strengthens the panel at that portion and substantially offsets all the buckling tendency resulting from tension in spring 28.

Various modifications of the structure illustrated will be apparent to those skilled in the art and for that reason I intend to limit myself only within the scope of the appended claims.

What I claim is:

1. A vehicle body panel comprising an embossed sheet of flexible material, a flexible frame of incomplete polygonal contour secured at its extremities to the upper face of the embossed portion of said sheet, and a strip of relatively rigid material having a thickness substantially equal to the depth of the embossment secured to the opposite face of the sheet in superposed relation to the incomplete side of said frame.

2. A vehicle body panel comprising an embossed sheet of flexible material, a flexible frame of incomplete polygonal contour secured at its extremities to the upper face of the embossed portion of said sheet, said sheet

including a rigidifying structure lying substantially within the plane of the unembossed portion of the same between the ends of said frame.

3 3. A vehicle body panel comprising an embossed sheet of flexible material, frame of incomplete polygonal contour secured at its extremities to the outer face of the embossed portion of said sheet, a strip of relatively rigid material of a thickness corresponding substantially to the depth of the embossment secured to the opposite face of the sheet in superposed relation to the incomplete side of said frame, and a coil spring under tension secured to the extremities of said frame.

4. In combination with a relatively flexible embossed panel body, a frame adapted to delineate the outer contour of a pocket, and having one incomplete side, secured at its extremities to said panel upon the upper face of the embossed portion, means lying substantially within the plane of the unembossed portion thereof for reinforcing said panel along that portion extending between the extremities of said frame, a coil spring under tension secured at each extremity to the ends of said frame, and trim material folded over said frame and stitched along the line thereof to the panel, said trim material being looped around the coil spring and the edge thereof stitched to the body portion of the trim material.

5. An automobile interior trim panel having a pocket comprising a panel of flexible thermoplastic composition fiber board material, a flexible wire frame of pocket contour terminating in ends spaced apart the dimensions of the mouth of the pocket and secured at said ends to one face of the panel, a substantially inflexible strip arranged on one side of said panel connecting said ends and holding them in spaced apart relationship, a yielding member tensioned between said ends on the opposite side of the panel to be held toward said inflexible strip, and fabric material secured about said frame to the panel and secured along said yielding tension member thereto to be held toward the panel thereby.

50 In testimony whereof, I, FRANCIS L. CHADWICK, sign this specification.

FRANCIS L. CHADWICK.
